UNITED STATES PATENT OFFICE.

WILLARD T. SEARS, OF BROOKLYN, NEW YORK, ASSIGNOR TO NILES-BEMENT-POND COMPANY, OF NEW YORK, N. Y., A CORPORATION OF NEW JERSEY.

CHANGE-SPEED MECHANISM.

1,342,928.

Specification of Letters Patent. Patented June 8, 1920.

Application filed October 30, 1918. Serial No. 260,224.

To all whom it may concern:

Be it known that I, WILLARD T. SEARS, a citizen of the United States, residing at Brooklyn, in the county of Kings and State 5 of New York, have invented certain new and useful Improvements in Change-Speed Mechanisms, of which the following is a specification.

The object of the invention is to provide a 10 change-speed mechanism which is capable of providing a relatively large number of speeds and which can be readily adjusted to provide any desired speed by means of a single control element.

15 The accompanying drawings show the preferred embodiment of the invention, but it will be understood that the drawings are for illustrative purposes only and are not to be construed as defining or limiting the 20 scope of the invention, the accompanying claims being relied upon for that purpose.

Of the drawings:

Figure 1 is a longitudinal vertical sectional view taken along the line 1—1 of 25 Fig. 2.

Fig. 2 is a longitudinal horizontal sectional view taken along the line 2—2 of Fig. 1.

Fig. 3 is an end view taken from the left.

30 Fig. 4 is a transverse vertical sectional view taken along the lines 4—4 of Fig. 1 and Fig. 2.

Fig. 5 is a longitudinal horizontal sectional view taken along the line 5—5 of 35 Fig. 1.

In the accompanying drawings I have shown a mechanism which is adapted to be used with or as a part of a radial drilling machine of the sort shown in my copending 40 application for radial drilling machines, Serial No. 256,430, filed October 1st, 1918. It will be understood, however, that the invention is not so limited and that it can be embodied in mechanisms different from that 45 herein shown and adapted for other purposes.

As illustrated, there is provided a housing 1 which is a part of the drilling machine and which serves as a support for the change-speed mechanism to which the present invention relates. Mounted in the housing 1 is a shaft 2 carrying a gear 3. This gear 3 can be considered as the initial drive element of the drilling machine proper and the change-speed mechanism is connected with this driv-

ing gear for the purpose of rotating it at any desired one of a plurality of speeds.

The various parts of the change-speed mechanism are carried by a frame 4 which is secured to the housing 1. Preferably the 60 frame is constructed in the form of a casing or housing which incloses many of the parts of the mechanism to retain lubricant and to exclude dust and dirt. Power is derived from any suitable source, and for purposes 65 of illustration, I have shown an electric motor 5 which is mounted on the top of the frame 4. Mounted on the armature shaft of the motor is a pinion 6 which is driven by the motor preferably by means of a friction 70 clutch 7. The pinion 6 meshes with a gear 8 on a longitudinal shaft 9, this shaft also carrying a gear 10.

Longitudinally mounted in the frame 4 are two parallel horizontal shafts 11 and 12. 75 The shaft 11 carries a gear 13 which meshes with the aforesaid gear 10, and the shaft 12 carries a gear 14 which meshes with the aforesaid gear 3. Fixedly secured on one of the shafts, in this case the shaft 11, are several gears of different diameters. Mounted on the other shaft, in this case the shaft 12, are several independently slidable gears 80 which correspond in number to the gears on the shaft 11 and which are adapted respectively to mesh with the said gears. The gears on the shaft 12 are preferably arranged in pairs, the gears of each pair being 85 slidably movable in unison. When these gears are so arranged in pairs, the gears on the shaft 11 are spaced apart so that any pair of gears can be moved in one direction to effect meshing of one of the gears thereof with its mate, and in the other direction to effect the meshing of the other of the gears 90 thereof with its mate. As illustrated, there are eight gears on the shaft 11 designated respectively by 15, 16, 17, 18, 19, 20, 21 and 22. The gears on the shaft 12 are designated by 23, 24, 25, 26, 27, 28, 29 and 30, these gears 95 being arranged in pairs, as illustrated.

For moving the slidable gears along the shaft 12, there is provided a longitudinally movable rod 31 which is parallel with the shafts 11 and 12. Means are provided 105 whereby the rod can be connected with any one of the pairs of gears to move the said pair in either direction to effect meshing. The rod 31 is preferably also movable angularly about its axis in order to effect the 110

aforesaid connection with the pairs of gears. Preferably, for moving the rod either longitudinally or angularly, there is provided a hand lever 32. This lever is transversely pivoted at 33 to a yoke 34. The yoke 34 is connected with a bushing 35 which surrounds the rod 31 and is angularly movable thereon in a bearing in the main frame 4. The rod 32 is forked to receive and closely fit the rectangular end of the rod 31, and each fork is provided with a slot which receives a pin 36 extending transversely through the rod. It will be seen that the rod 31 can be moved longitudinally by swinging the lever 32 about its pivot at 33. The rod can be moved angularly by swinging the lever about the axis of the rod, the bushing 35 turning in its bearing.

The mechanism whereby any pair of gears 20 may be connected with the rod 31 is preferably constructed as follows: Each pair of gears is formed with a grooved hub and arms 37, 38, 39 and 40 are fitted in the respective grooves so as to be capable of angular movement about the axis of the shaft 12. The arms are provided respectively with fingers 37^a, 38^a, 39^a and 40^a which are adapted respectively to be embraced by forks 37^b, 38^b, 39^b and 40^b secured to the rod 31. 25 The forks are arranged at different angular positions on the rod 31 so that by turning the rod about its axis any fork can be brought into association with the corresponding finger, and the arrangement is such 30 that only one fork can be engaged with a finger at one time. When the operator desires to move any pair of gears in either direction, he first turns the rod 31 by means of the handle 32 so as to bring one of the 35 forks into engagement with the finger corresponding to the pair of gears which is to be moved. If, for instance, the pair of gears 23—24 is to be moved, the rod 31 is turned to bring the fork 37^b into engagement 40 with the finger 37^a. Then the operator, by moving the lever 32 about its pivotal axis at 33, can move the rod 31 longitudinally in either direction and thus either bring the gear 23 into mesh with the gear 15, as illustrated, or bring the gear 24 into mesh with the gear 16. The other gears are not moved as the corresponding fingers are not engaged by the forks on the rod 31.

In order that none of the gears may be 55 moved accidentally, there is preferably provided in connection with each arm a locking mechanism which prevents the movement of the arm and the corresponding gears except when connected with the rod 31. As illustrated, there are positioned respectively adjacent the arms, notched lugs 41, 42, 43 and 44, the notches of the lugs being so positioned as to be adapted to receive teeth 45 formed on the respective arms. Means is 60 provided in connection with each arm for

pressing it forward so as to hold its tooth 45 in engagement with the corresponding notch. As illustrated, this means consists of a spring-pressed plunger 46 mounted in an aperture in the arm and engaging a boss 70 47 on the main frame. In order that the locking device for each arm may be released when the arm is about to be moved by the rod 31, there are provided cams 48 associated respectively with the forks 37^b 75 to 40^b and adapted respectively to engage the fingers 37^a to 40^a. When the rod 31 is turned to effect engagement between any fork and one of the fingers, the corresponding cam 48 engages the finger and presses 80 the corresponding arm backward, thus disengaging the tooth 45 from its notch.

In order to prevent the operator from inadvertently disconnecting the rod 31 from a pair of gears when the said pair of gears 85 is in an operative position, I provide means which makes it impossible for the rod to be turned except when in its neutral position with all of the gears out of mesh. The means provided for this purpose consists of 90 a slotted bracket 49 through which the lever 32 extends. This bracket is provided with a main transverse slot 50 through which the lever 32 may be moved to turn the rod 31 about its axis. Associated with the main 95 slot 50 and extending transversely thereof are four longitudinal slots 51, 52, 53 and 54 which are positioned to receive the lever 32 and permit its pivotal movement when one of the forks is engaged with the corresponding finger. It will be seen that the bracket 49 serves to prevent the rod 31 from being turned except when in neutral position, and that the bracket further serves to prevent the rod 41 from being moved longitudinally 100 to move a pair of gears, except when it has been moved angularly to a predetermined extent so as to be completely connected with one of the arms.

What I claim is:

1. In a change-speed mechanism, the combination of two parallel shafts, a plurality of differently diametered gears fixed on one shaft, a plurality of gears independently slidable on the other shaft and adapted to 115 mesh respectively with the gears on the first shaft, a longitudinally and angularly movable rod positioned parallel with the shafts, a single means for moving the rod longitudinally and angularly, and means 120 comprising a plurality of gear-engaging elements dependent on the angular movement of the rod whereby the rod may be connected with any one of the slidable gears to move it longitudinally into or out of 125 mesh with its mate.

2. In a change-speed mechanism, the combination of two parallel shafts, a plurality of differently diametered gears fixed on one shaft, a plurality of gears independently 130

- slidable on the other shaft and adapted to mesh respectively with the gears on the first shaft, a longitudinally and angularly movable rod positioned parallel with the 5 shafts, a single means for moving the rod longitudinally and angularly, means comprising a plurality of gear-engaging elements dependent on the angular movement of the rod whereby the rod may be connected with 10 any one of the slidable gears to move it longitudinally into or out of mesh with its mate, and means supplemental to the rod and adapted to engage the gear-engaging elements for locking each slidable gear not 15 connected with the rod out of mesh with its mate.
3. In a change-speed mechanism, the combination of two parallel shafts, a plurality of differently diametered gears fixed on one 20 shaft, a plurality of gears independently slidable on the other shaft and adapted to mesh respectively with the gears on the first shaft, a longitudinally and angularly movable rod positioned parallel with the 25 shafts, a single means for moving the rod longitudinally and angularly, means comprising a plurality of gear-engaging elements dependent on the angular movement of the rod whereby the rod may be connected 30 with any one of the slidable gears to move it longitudinally into or out of mesh with its mate, and means supplemental to the rod and adapted to engage the gear-engaging elements for locking each slidable gear not 35 connected with the rod out of mesh with its mate, the said locking means for any gear being released by the rod when the rod is angularly moved to effect connection with the said gear.
4. In a change-speed mechanism, the combination of two parallel shafts, a plurality of differently diametered gears fixed on one shaft, a plurality of gears independently slidable on the other shaft and adapted to 40 mesh respectively with the gears on the first shaft, a longitudinally and angularly movable rod positioned parallel with the shafts, a single means for moving the rod longitudinally and angularly, means comprising a plurality of gear-engaging elements dependent on the angular movement of the rod whereby the rod may be connected 45 with any one of the slidable gears to move it longitudinally into or out of mesh with its mate, and means for preventing angular movement of the rod to effect 50 connection or disconnection except when all of the slidable gears are out of mesh.
5. In a change-speed mechanism, the combination of two parallel shafts, a plurality of differently diametered gears fixed on one shaft, a plurality of gears independently slidable on the other shaft and adapted to mesh respectively with the gears on the 55 first shaft, a longitudinally and angularly 60 movable rod positioned parallel with the shafts, a single means for moving the rod longitudinally and angularly, means comprising a plurality of gear-engaging elements dependent on the angular movement of the rod whereby the rod may be connected with any one of the slidable gears to move it longitudinally into or out of mesh with its mate, and means for preventing longitudinal movement of the rod except when it is moved angularly to a predetermined extent to effect full connection with one of the slidable gears.
6. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally and angularly movable rod positioned parallel with the shafts, a single means for moving the rod longitudinally and angularly, means comprising a plurality of gear-engaging elements dependent on the angular movement of the rod whereby the rod may be connected with any one of the slidable gears to move it longitudinally into or out of mesh with its mate, means for preventing longitudinal movement of the rod except when it is moved angularly to a predetermined extent to effect full connection with one of the slidable gears.
7. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally and angularly movable rod positioned parallel with the shafts, a single means for moving the rod longitudinally and angularly, means comprising a plurality of gear-engaging elements dependent on the angular movement of the rod whereby the rod may be connected with any one of the slidable gears to move it longitudinally into or out of mesh with its mate, means for preventing longitudinal movement of the rod except when it is moved angularly to a predetermined extent to effect full connection with one of the slidable gears.
8. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally and angularly movable rod positioned parallel with the shafts, a single means for moving the rod longitudinally and angularly, means comprising a plurality of gear-engaging elements dependent on the angular movement of the rod whereby the rod may be connected with any one of the slidable gears to move it longitudinally into or out of mesh with its mate, means for preventing longitudinal movement of the rod except when it is moved angularly to a predetermined extent to effect full connection with one of the slidable gears.

first shaft, a longitudinally and angularly movable rod positioned parallel with the shafts, means dependent on the angular movement of the rod whereby the rod may be connected with any one of the slidable gears to move it longitudinally into or out of mesh with its mate, a handle mounted on the rod for moving it angularly and longitudinally, and means including a longitudinally and transversely slotted bracket 5 enclosing the handle and adapted to prevent angular movement of the rod to effect connection or disconnection except when all of the slidable gears are out of mesh and for preventing longitudinal movement of the rod except when it is moved angularly to a predetermined extent to effect full connection with one of the slidable gears.

9. In a change-speed mechanism, the combination of two parallel shafts, a plurality of differently diametered gears fixed on one shaft, a plurality of pairs of gears independently slidable on the other shaft whereby either of the gears of any pair may be brought into mesh with a mating gear on the first shaft, a longitudinally movable rod positioned parallel with the shafts, means including a plurality of gear-engaging elements on the rod whereby the rod may be connected with any one of the slidable pairs of gears, and means mounted on the rod to move the rod longitudinally in either direction to bring one of the gears thereof into or out of mesh with its mate.

35 10. In a change-speed mechanism, the combination of two parallel shafts, a plurality of differently diametered gears fixed on one shaft, a plurality of pairs of gears independently slidable on the other shaft, whereby either of the gears of any pair may be brought into mesh with a mating gear on the first shaft, a longitudinally and angularly movable rod positioned parallel with the shafts, means including a plurality of gear-engaging elements on the rod and dependent on angular movement of the rod whereby the rod may be connected with any one of the slidable pairs of gears, and means mounted on the rod to move the rod longitudinally in either direction to bring one of the gears thereof into or out of mesh with its mate.

11. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally movable rod positioned parallel with the shafts, arms connected respectively with the slidable gears and supported independently of the rod, and a single means whereby the rod may be moved to connect it with any one 60 of the arms to bring the corresponding

slidable gear into or out of mesh with its mate.

12. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally and angularly movable rod positioned parallel with the 70 shafts, arms connected respectively with the slidable gears and supported independently of the rod, means dependent on angular movement of the rod whereby the rod may be connected with any one of the arms to bring the corresponding slidable gear into or out of mesh with its mate, and a single means for moving the rod longitudinally and angularly.

13. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally movable rod positioned parallel with the shafts, arms connected respectively with the slidable gears and supported independently of the rod, a single means whereby the rod may be moved 90 to connect it with any one of the arms to bring the corresponding slidable gear into or out of mesh with its mate, and means engaging the arms for locking each slidable gear not connected with the rod out of mesh 100 with its mate.

14. In a change-speed mechanism, the combination of two parallel shafts, a plurality of differently diametered gears fixed on one shaft, a plurality of gears independently slidable on the other shaft and adapted to mesh respectively with the gears on the first shaft, a longitudinally movable rod positioned parallel with the shafts, arms mounted respectively on the slidable gears 110 and angularly movable about the axis of said gears, and means whereby the rod may be connected with any one of the arms to bring the corresponding slidable gear into or out of mesh with its mate.

15. In a change-speed mechanism, the combination of two parallel shafts, a plurality of differently diametered gears fixed on one shaft, a plurality of gears independently slidable on the other shaft and adapted 120 to mesh respectively with the gears on the first shaft, a longitudinally movable rod positioned parallel with the shafts, arms connected respectively with the slidable gears and angularly movable about the axis of the 125 said gears, means whereby the rod may be connected with any one of the arms to bring the corresponding slidable gear into or out of mesh with its mate, and means engaging the arms and dependent on the angular 130

movement thereof for preventing longitudinal movement except when connected with the rod.

16. In a change-speed mechanism, the combination of two parallel shafts, a plurality of differently diametered gears fixed on one shaft, a plurality of gears independently slideable on the other shaft and adapted to mesh respectively with the gears on the first shaft, a longitudinally and angularly movable rod positioned parallel with the shafts, arms connected respectively with the slideable gears and angularly movable about the axis of the said gears, means whereby the rod may be connected with any one of the arms to bring the corresponding slideable gear into or out of mesh with its mate, and notched lugs respectively adjacent the arms for engaging them and preventing longitudinal movement except when connected with the rod.

17. In a change-speed mechanism, the combination of two parallel shafts, a plurality of differently diametered gears fixed

on one shaft, a plurality of gears independently slideable on the other shaft and adapted to mesh respectively with the gears on the first shaft, a longitudinally and angularly movable rod positioned parallel with the shafts, arms connected respectively with the slideable gears and angularly movable about the axis of the said gears, means dependent on angular movement of the rod whereby the rod may be connected with any one of the arms to bring the corresponding slideable gear into or out of mesh with its mate, means engaging the arms and dependent on the angular movement thereof for preventing longitudinal movement except when connected with the rod, and means dependent on the angular movement of the rod for releasing the arm with which the rod is connected.

In testimony whereof I hereto affix my signature.

WILLARD T. SEARS.
